FOLDING BOX

Roderick W. Hoag, Melrose, Mass.

Application October 16, 1936, Serial No. 105,984

3 Claims. (Cl. 229—31)

The invention relates to improvements in folding boxes of the type which automatically lock the walls thereof in upright position upon being brought to such position.

5 My invention consists in the folding box as hereinafter described and claimed.

Of the accompanying drawings:

Figure 1 is a plan view of the blank from which the box may be formed.

10 Figure 2 is a plan view of the blank showing its condition after end wall flap extensions have been folded.

Figure 3 is a plan view of the blank showing areas to which adhesive may be applied in making the box.

Figure 4 is a plan view of the blank showing the condition thereof after the front and rear margins of the blank have been folded against the center area of the blank.

20 Figure 5 is similar to Figure 4 except that areas are shown to which adhesive may be applied in producing the box.

Figure 6 is a plan view of the completed box, in flat condition.

25 Figure 7 is a plan view of the box in set up form.

Figure 8 is a front elevation of the box shown in Fig. 7.

30 Figure 9 is an end elevation of the box shown in Fig. 8.

Figure 10 is the same as Figure 1, except that it is shown turned at an angle of 90°.

35 Figures 11 to 15 inclusive, illustrate the progressive steps of a method for making a modified form of box from a blank shown in Figure 10.

Figure 16 is a plan view of the box shown in Figure 15, after it has been set up.

Figure 17 is an end elevation of the box shown in Fig. 16.

40 Figure 18 is a front elevation of the box shown in Fig. 17.

Figure 19 is a perspective view of the box shown in Figs. 16, 17 and 18, tilted so as to show a portion of the interior thereof.

45 Figure 20 is a perspective view of the box shown in Figs. 7, 8 and 9, tilted so as to show a portion of the interior thereof.

50 Referring to Figure 1, there is illustrated a cut and scored blank of suitable material, such as paper box board, scored lines are represented by dash lines 10 to 17 inclusive and 20, and cut lines are represented by lines 18 and 19. The said score lines and cut lines effect a division of 55 the blank to form a bottom section 1 for the box,

a rear wall section 2, a front wall section 3, end wall sections 4 and 5, end wall flaps 6, end wall flap extensions 7 crease-hinged to said flaps 6, end wall corner segments 8 and front and rear wall corner segments 9. Said corner segments 8 and 9 5 form a bellows fold element at each corner of the box.

In producing the box in collapsed condition from a cut and scored blank (Fig. 1), the end wall flap extensions 7 are folded against end wall flaps 6 (Fig. 2), predetermined areas 21 (Fig. 3) are then treated with adhesive so that when the blank is folded on lines 10, 11, 14 and 15 (Figs. 1, 2, 3 and 4) the end wall corner segments 8 will contact the adhesively treated areas 21 (Fig. 3). 15 After said folding operation the blank is in the condition illustrated by Fig. 4. The upward facing surfaces of the front and rear wall sections 3 and 2 (Fig. 5) are then adhesively treated at predetermined areas 22. The end wall sections 4 20 and 5 together with the front and rear wall corner segments are then folded on lines 12, 13 and 17, thus causing the folded end wall flap extensions 7 to contact the adhesively treated areas 22 to 25 complete the box in collapsed condition ready to be instantly set up for use.

When it is desired to set up the box for use, the front and rear walls 3 and 2 are simply raised and bent outward, whereupon the front and rear wall corner segments 9 in each corner will automatically snap into position parallel with the corresponding end wall section, thus automatically locking and keeping the box in upright position, the said corner segments constituting keepers for the purpose.

35 The form of construction and the method of making the box illustrated in Figs. 10 to 19 inclusive, is the same as that illustrated in Figs. 1 to 9 inclusive and Fig. 20, except that the end wall flap extensions 7 are secured to the inside 40 of the box and the end wall corner segments 8 are secured to the outside of the box. In the method for securing this result a blank Fig. 10, which is identical to the blank shown in Figure 1, the end wall flap extensions 7 are folded against the upward facing surface of the end wall flaps 6 (Fig. 11), predetermined areas 23 are then treated with adhesive (Fig. 12), the blank is then folded on lines 12, 13 and 17 with the result that end wall flap extensions 7 will contact the adhesively treated areas 23. The blank is then in the condition illustrated by Figure 13. Adhesive is then applied to predetermined areas 24 (Fig. 14) on the upward facing surfaces of the front and rear walls. The blank is then folded on lines 10, 11, 55

14 and 15 with the result that end wall corner segments 8 will contact the adhesively treated areas 24 thus completing the box in collapsed condition.

5 While I have illustrated and described the preferred forms of construction for carrying my invention into effect, these are capable of variation and modification without departing from the spirit of the invention.

10 I have shown the cut lines 18 and 19 (Figs. 1 and 10) as the preferred form of cuts to be provided in the blank, but the cuts may be varied without departing from my invention. Said cuts may be in the form of one straight line extending from each end of the end wall sections or the cuts 15 may be curved or irregular in shape, provided they extend from the ends of the end wall sections and intersect the scored lines extending from the adjacent corner of the bottom section to the corresponding outside corner of the blank at each of 20 the four corners.

25 The score lines 11, 14 and 15 are shown as being in one straight line (Figs. 1 and 10) as are score lines 13 and 17, also score lines 16 and 20 are shown as one straight line. These score lines are 30 illustrated in this way for simplicity, but in practice it may be desirable, when fairly thick material is used, to have some of the lines slightly out of line with each other, or at a slight angle with each other, to compensate for the thickness of the material from which the box blank is made in order to permit folding the walls and corners of the box to flat condition and so that the box may be set up without binding or cramping.

35 Instead of applying adhesive to areas 21 (Fig. 3), 22 (Fig. 5), 23 (Fig. 12) and 24 (Fig. 14), the adhesive may be applied directly to the corner segments 8 and flap extensions 7, without departing from the spirit of my invention.

40 I have shown as a preferred embodiment of my invention, that end wall corner segments 8 should be secured to the end walls 4 and 5 at areas 21 (Fig. 3), but it is not necessary that said corner segments 8 be so secured, because the box

will be effective for many uses without being fastened to the inside of the end walls.

Having described my invention, what I claim is:

1. A folding box comprising a bottom, upright front and rear walls and end walls, the said end walls being provided at each end thereof with a flap, and each flap having crease-hinged thereto a flap extension secured to the outside surface of the corresponding front or rear wall; a bellows fold element at each corner of the box being integral with a portion of the end edge of the end wall and integral with the corresponding end edge of the front or rear wall, one surface of said bellows fold element being secured to the inside surface of the end wall, substantially as described. 10

15 2. A folding box comprising a bottom, upright front and rear walls and end walls, the said end walls being provided at each end thereof with a flap, and each flap having crease-hinged thereto a flap extension secured to the inside surface of the corresponding front or rear wall; a bellows fold element at each corner of the box being integral with a portion of the end edge of the end wall and integral with the corresponding end edge of the front or rear wall, one surface of said bellows fold element being secured to the outside surface of the end wall, substantially as described. 20

25 3. A folding box comprising a bottom, upright front and rear walls and end walls, the said end walls being provided at each end thereof with a flap, and each flap having crease-hinged thereto a flap extension secured to the corresponding front or rear wall; a bellows fold element at each corner of the box being integral with a portion of the end edge of the end wall and integral with the corresponding end edge of the front or rear wall, one surface of each bellows fold element being secured to the surface of the corresponding end wall; the said flap extension and the bellows fold element at each corner of the box being secured, one to an outside surface of the box and the other to an inside surface of the box. 30

40 RODERICK WM. HOAG.
